DESIGN FOR A GAME BOARD

Russell Kent Harsh, Dallas, Tex.

Application September 26, 1933, Serial No. 49,346

Term of patent 3½ years

To all whom it may concern:

Be it known that I, RUSSELL KENT HARSH, a citizen of the United States, residing at Dallas, in the county of Dallas and State of Texas, have invented a new, original, and ornamental Design for Game Boards, of which the following is a specification, reference being had to the accompanying drawing, forming a part thereof.

The broken line presentation in Figure 1 denotes a continuation of the design shown over the entire upper surface of the disc.

I claim:

The ornamental design for a game board, as shown and described.

RUSSELL KENT HARSH.
